UNITED STATES PATENT OFFICE.

BENJAMIN F. GRIMSHAW, OF STOCKTON, CALIFORNIA.

DESIGN FOR A SIGNPOST.

Application filed May 18, 1927. Serial No. 22,035. Term of patent 3½ years.

To all whom it may concern:

Be it known that I, BENJAMIN F. GRIMSHAW, a citizen of the United States, residing at Stockton, in the county of San Joaquin and State of California, have invented a new, original, and ornamental Design for a Signpost, of which the following is a specification, reference being had to the accompanying drawing, forming part thereof, and in which,

I claim:

The ornamental design for a signpost as shown.

BENJAMIN F. GRIMSHAW.
